UNITED STATES PATENT OFFICE.

ELLIS J. G. PHILLIPS, OF AURORA, ILLINOIS. ASSIGNOR TO RICHARDS-WILCOX MANUFACTURING COMPANY, OF AURORA, ILLINOIS, A CORPORATION OF ILLINOIS.

HINGE.

Application filed May 31, 1921. Serial No. 473,695.

To all whom it may concern:

Be it known that I, ELLIS J. G. PHILLIPS, a citizen of the United States, and a resident of Aurora, in the county of Kane and State of Illinois, have invented certain new and useful Improvements in Hinges, of which the following is a specification, reference being had to the accompanying drawings.

10 In connection with the supporting in position of large heavy doors, and particularly in connection with hingedly supporting in position the end member of a door structure that comprises a plurality of door-sections that are hinged together after the manner illustrated in Letters Patent No. 1,357,299, granted upon my application, it is frequently found necessary or desirable that the pintles of the hinges be located at 15 some little distance from one edge of the doorway so as to allow such heavy single door, or the door made up of a number of members connected together as stated, to be turned to stand, when in open position, entirely clear of the doorway. At other times 20 it is desirable that such hinge-pintles be located close to the edge of the doorway.

As generally constructed the long strap member of each of the hinges that is attached to the door has quite a number of 25 openings in it for the passage of screws that hold such member to the door, and because of the greater strain that is imposed upon the screws that are located nearer the inner 30 end of such strap member such inner end portion is usually wider than toward its other end in order that more screws may conveniently be located near such inner end. When, however, the pintle is set back away 35 from the edge of the door opening, these holes in such inner end portion of the strap member are not only rendered useless by being positioned over the door jamb or over a portion of the door that is so close to its 40 edge as to preclude the use of screws in such holes, but by reason of their non-use they are objectionable in many instances because of their unsightliness.

It is the object of my invention to provide 45 a hinge construction wherein the pintle may be located either close to the edge of the doorway or at some considerable distance therefrom, and in either case have the inner end portion of the long strap member secured firmly to the door without the use of

screws therethrough, thus entirely obviating the making of screw-holes through such portion of the strap and, of course, doing away with the unsightly appearance above mentioned when the hinge pintle is located at 50 some little distance from the doorway, as described. I accomplish this object as shown in the drawing and hereinafter particularly described.

In the drawing,—

Fig. 1 is a front elevation of a strap hinge secured upon a door and the pintle therefor being shown as located at a considerable distance from the edge of the doorway, the inner end portion of the long strap member of 60 the hinge being unprovided with the usual screw openings therethrough, and such inner end portion being secured to the door by my improved means;

Fig. 2 is an edge view of the hinge device shown in Fig. 1, the door and jamb being in section;

Fig. 3 is an enlarged vertical section taken at line 3—3 of Fig. 1, except that the pintle is shown in elevation; and

Fig. 4 is a vertical section taken at line 4—4 of Fig. 1.

Referring to the several figures of the drawing—5 indicates an ordinary heavy door, or it may be the inner section or leaf 85 of a plurality of door members that are hingedly connected together as shown and described in my said Letters Patent. 6 indicates a jamb to which the door member 5 is hinged. 7 indicates a strap hinge which, 90 as is generally the case, is wider at its inner end than at its other end. Such hinge member as heretofore constructed has been provided with screw holes therethrough at intervals throughout its length, and as stated, 95

has frequently had through its wider inner end portion more of such screw holes than at other places, whereby by the use of a greater number of attaching screws at such end the hinge is better able to withstand 100 the sagging strain of the door. I retain in the hinge strap member certain of such screw holes, through which, as shown screws 8 are inserted. The screw holes that I retain are, however, only such as would 105 be capable of use for the insertion of screws into the door under any feasible adjustment of the hinge that would position its pintle at a distance from the edge of the doorway. In order to firmly secure such unapertured 110

inner end portion of the hinge strap to the door I provide a clip 9 the central portion of which, as best shown in Fig. 4, is struck up just sufficiently to provide a flat surface 5 that bears closely against the outer surface of the hinge strap while the end portions of such clip bear evenly against the face of the door. The two shoulders 11 that connect the raised central part of the clip 10 and the door-attaching ends thereof are so formed and disposed as to bear tightly against the side edges, respectively, of the strap 7 so as to effectually prevent any relative movement between such strap and the 15 clip when the clip is secured in place by the screws 10 that pass through the end portions of the clip as shown, which relative movement could not be relied upon being wholly prevented solely by the frictional contact of the inner face of the clip with the surface of the hinge strap. In order that the desired contact of the said shoulders 11 of the clip with the edges of the hinge strap shall be maintained in any 20 longitudinally-adjusted position of the hinge device it is essential, of course, that the inner end portion of the strap member 7, which is ordinarily wider than towards the other end, as stated, shall be of uniform 25 width for a sufficient distance to permit of the required close fit of the clip when the pintle of the hinge is positioned close to the edge of the doorway or at the extreme distance that it is liable to be placed therefrom 30 or at any point intermediate of those two locations. If the margins of the strap member were not parallel to provide for such uniform width it is evident that the required fit of the shoulders 11 against the 35 strap's edges could not be had in the different position to which the hinge as a whole was adjusted.

12 indicates a bracket adapted to be screwed to the jamb 6 at any desired distance from the edge of the doorway. The bracket carries two forwardly-projecting ears 13 in which is mounted a pintle 14 that passes through an eye 15 that is formed integral with the strap member 7 at the inner end thereof, such inner end portion 50 that carries said eye being bent outwardly away from the main or body portion of the strap 7, as best shown in Fig. 2, so as to lie between the ears 13 with the eye in 55 position to receive the pintle.

What I claim as my invention and desire to secure by Letters Patent, is—

1. In combination, a hinge comprising a strap member and a pintle-supporting mem-

ber adapted to be attached to a door and a jamb, respectively, a clip adapted to be attached to the door and overlie and fit different parts of the inner end portion of the strap member to permit said pintle-supporting member to be located at different distances from the edge of the door, and other fastening means inserted through an opening in the outer end portion of the strap member.

2. In combination, a hinge comprising a strap member and a pintle-supporting member adapted to be attached to a door and a jamb, respectively, a clip adapted to be attached to the door and overlie a predetermined part of the inner end portion of the strap member to permit it to be located at varying distances from the edge of the door, and other fastening means inserted through an opening in the outer end portion of the strap member, such opening being approximately the same size as said fastening means.

3. In combination, a hinge comprising a strap member and a pintle-supporting member adapted to be attached to a door and a jamb, respectively, a clip adapted to be attached to the door above and below the strap member and overlie different parts of the inner end portion of the strap member to permit said pintle-supporting member to be located at different distances from the edge of the door, and other fastening means inserted through an opening in the outer end portion of said strap member.

4. In combination, a hinge comprising a strap member and a pintle-supporting member adapted to be attached to a door and a jamb, respectively, said strap member being adapted to be attached to the door by fastening means inserted through an opening in its outer end portion, and a clip overlying the inner end portion of said strap member and adapted to be attached to the door at varying distances from said first-named fastening means.

5. A hinge comprising in combination a strap member and a pintle-supporting member adapted to be attached to a door and jamb, respectively, said strap member having the upper and lower edges of its inner end portion substantially straight and parallel, and a clip adapted to be secured at its ends to the door and overlying said inner portion of the strap member and having shoulders that engage said straight parallel edges, said strap member having an opening in its outer end portion for the passage of other securing means.

ELLIS J. G. PHILLIPS.
